UNITED STATES PATENT OFFICE.

WILLIAM A. YUNG, OF PITTSBURGH, PENNSYLVANIA.

MELTING FURNACE.

Application filed April 15, 1925. Serial No. 23,289.

To all whom it may concern:

Be it known that I, WILLIAM A. YUNG, a citizen of the United States, and resident of Pittsburgh, in the county of Allegheny and 5 State of Pennsylvania, have invented certain new and useful Improvements in Melting Furnaces, of which the following is a specification.

This invention relates to melting furnaces 10 and while not limited thereto, relates more particularly to glass melting furnaces, and has for one of its objects the provision of such a furnace so designed as to materially reduce the radiating surface of the molten 15 mass, and also designed so as to utilize the maximum number of heat units from the fuel used to melt the material.

Another object is to provide a furnace of this class in which the refined molten mass 20 of glass is separated from the partly melted stock in the furnace, thereby improving the quality of glass to be discharged from the furnace.

A further object is to provide a furnace 25 having the novel design, construction and combination of parts hereinafter described and illustrated in the accompanying drawings—

Figure 1 is a sectional plan of a furnace 30 constructed in accordance with my invention.

Figure 2 is a transverse sectional elevation through the furnace.

Figure 3 is a partial longitudinal sectional 35 elevation on the line III—III of Figure 1.

Referring more particularly to the drawings, the numeral 2 designates the supporting structure or base for the furnace. The furnace comprises a flat bottom wall 3, side 40 walls 4 and 5, front and back end walls 6 and 7, respectively, arched top or roof 8, and a dividing wall 9 extending the full length of the furnace and dividing the furnace into two separate chambers A and B. 45 All the walls of the furnace are formed from brick or other suitable refractory material, and the side and end walls are supported by suitable buckstays 10.

The front end wall 6 of the furnace is 50 provided with a fuel burner port opening 11 communicating with the initial melting chamber A of the furnace, and having a burner 11^a mounted therein of any standard construction adapted to burn either gaseous or liquid fuel. An outlet port opening 12 is also provided in the front end wall 6 and

communicates with the forward portion of the chamber B. The port 12 opens into a flue 12^a which leads to a stack (not shown) or to a suitable recuperating chamber, and 60 then to a stack if desired.

The side wall 5 of the furnace is provided with a suitable inlet opening 14 which opens into a suitable stock chamber 15 generally termed a "dog-house," into which the stock 65 and broken glass is fed and from which it feeds through the opening 14 into the chamber A of the furnace.

The side wall 4 of the furnace is provided adjacent its forward end with a pair of 70 work openings 16, through which the molten refined glass is gathered, or otherwise discharged.

The dividing wall 9 extends the full 75 length of the furnace and from the bottom wall 3 to the roof, so as to completely separate the interior of the furnace into the chambers A and B, and such wall is provided at its rear end with a small port opening 17 at its lower edge through which the molten glass may flow from the chamber A to the chamber B. A materially larger port opening 18 is provided at the rear end of the wall 9 at a point above the port 17 through which the products of combustion 80 pass from the chamber A to the chamber B. 85

The side walls 4 and 5 are offset outwardly as at 19, and the dividing wall 9 is composed of a lower portion 9^a of materially greater thickness than the upper portion 9^b, so as to form a relatively narrow flow path along the bottom of the furnace for the molten glass, and a relatively wider flow path above the molten glass for the products of combustion. 90

The lower portion 9^a of the wall 9 is provided with an air duct 20 to permit a flow of air through the interior of the wall to cool the same. 95

During the operation of the furnace if it 100 is desired to vary the area of the port 18 so as to regulate the flow of the products of combustion, bricks may be laid along the lower edge of the port 18, such bricks being inserted by the use of tongs or other suitable tools through the work openings 16. 105

In operation, the broken glass and other stock is shoveled or otherwise fed into the "dog-house" 15 and falls by gravity or is otherwise fed into the initial melting chamber A of the furnace. The material is melted in the chamber A and forms a fluid mass 110.

which flows along the bottom of the furnace in a restricted or narrow path, due to the thick lower portion 9^a of the dividing wall 9 and the lower inset portions of the side walls 4 and 5. The molten or fluid glass will flow along the bottom of the furnace from the front to the back and then through the small port opening 17 into the chamber B, where its direction of flow will be reversed, and it will flow forward in the chamber B to the forward end of the furnace where it will be removed or discharged through the work openings 16.

The products of combustion from the furnace will pass from the forward end of the chamber A, rearwardly over the mass of molten glass, through the port opening 18 at the rear end of the wall 9, and then forwardly over the mass of molten glass in the chamber B to the port or opening 12 in the front wall 6 of the furnace, and thence to the stack.

The confining of the glass to a narrow flow path as it passes through the furnace materially reduces the radiating surface of the mass and, therefore, materially reduces the amount of heat necessary to melt a given quantity of glass over that necessary in previous furnace constructions, and the confining of the gases or products of combustion to a flow path over the entire mass of glass and compelling such gases to flow along the entire length of both the chambers A and B, extracts the maximum heat units from the gases. Therefore, materially less fuel is necessary to melt a given quantity of glass in a furnace constructed in accordance with this invention than with any furnaces now in use.

It will also be noted that due to the fact that all the glass must travel through the same path and be subjected to the melting heat for the same length of time, a more uniform product is obtained than with furnaces where the molten glass may take a short path to the work openings.

While I have described my invention as pertaining primarily to a glass melting furnace, it will be understood that I do not wish to limit myself to this use exclusively, since the same construction may be used for furnaces used in melting metals and other materials. The outlet for the products of combustion may be located in the roof or side walls adjacent to the end wall 7 instead of in the end wall as shown, and other changes may be made within the scope of my invention as defined in the appended claims.

I claim:

1. A melting furnace comprising a substantially rectangular body portion, a wall dividing said furnace into two melting chambers, and having separate openings at one end for the passage of the melted ma-

terial and products of combustion from one chamber to the other, a fuel burner at the end of one of said chambers opposite said openings in said dividing wall, an outlet port for the products of combustion at the end of said other chamber opposite said openings in said dividing wall, and work openings for the removal of the melted material in said last named chamber.

2. A glass melting furnace comprising a rectangular body portion comprising a bottom wall, side walls, front and back end walls, roof, and a longitudinally extending dividing wall extending from bottom to roof and end to end of the furnace forming two chambers, a pair of port openings adjacent the rear end of said dividing wall for the passage of the molten glass and products of combustion from one chamber to the other, a burner port in the front end wall of one of said chambers, a glass stock inlet port adjacent the forward end of said last named chamber, an outlet port for the products of combustion at the forward end of the other of said chambers, and work openings for the discharge of the glass adjacent the forward end of said last named chamber.

3. A melting furnace comprising a rectangular body portion composed of a substantially flat bottom wall, side walls, front and back end walls, arched roof, and a longitudinally extending dividing wall extending from bottom to roof and end to end of the furnace forming two chambers, said side walls being offset outwardly intermediate their upper and lower edges and said dividing wall being materially thicker from its bottom upwardly to a point intermediate the bottom and roof of said furnace to thereby form relatively narrow flow channels for the molten material and relatively wide flow channels for the products of combustion above the molten material, a burner port and an outlet port for the products of combustion formed in said furnace, and said dividing wall being provided with openings for the passage of molten material and the products of combustion from one chamber to the other.

4. A melting furnace comprising a rectangular body portion composed of a substantially flat bottom wall, side walls, front and back end walls, arched roof, and a longitudinally extending dividing wall extending from bottom to roof and end to end of the furnace forming two chambers, said side walls being offset outwardly intermediate their upper and lower edges and said dividing wall being materially thicker from its bottom upwardly to a point intermediate the bottom and roof of said furnace to thereby form relatively narrow flow channels for the molten material and relatively wide flow channels for the products of combustion

- above the molten material, a burner port adjacent the forward end of one of said chambers, an outlet port adjacent the forward end of the other chamber, openings adjacent 5 the rear end of said dividing wall to permit the molten material and products of combustion to flow from one chamber into the other, and suitable work openings through which the molten material is discharged.
- 10 5. A glass melting furnace comprising a rectangular body portion composed of a substantially flat bottom wall, side walls, front and back end walls, arched roof, and a longitudinally extending dividing wall extending 15 from bottom to roof and end to end of the furnace forming two chambers, said side walls being offset outwardly intermediate their upper and lower edges and said dividing wall being materially thicker from its bottom 20 upwardly to a point intermediate the bottom and roof of said furnace to thereby form relatively narrow flow channels for the molten glass and relatively wider flow paths for the products of combustion 25 above the molten glass, an inlet or feed opening for the glass stock in one of said chambers adjacent the front end of said furnace, a fuel burner entering said last named chamber at the front end thereof, an outlet opening 30 for the products of combustion in the front end wall of the other of said chambers, work openings adjacent the forward end of said last named chamber, a port in the lower portion of said dividing wall for passage of 35 the molten glass from one of said chambers to the other, and a second and materially larger port located in the upper part of said dividing wall for the passage of the products of combustion from one chamber to 40 the other, said ports being located adjacent the rear end of said dividing wall, so that the glass and products of combustion must travel from the front end of one chamber to the rear, then into the rear of the second
- chamber and forward to the front end of the 45 second chamber to be discharged.
6. In a glass melting furnace comprising a rectangular body portion composed of a bottom wall, side walls, front and back end walls and roof, a dividing wall extending 50 longitudinally of said furnace from end to end and bottom to roof forming two chambers, openings through said dividing wall adjacent one end for the passage of glass and the products of combustion from one 55 chamber to the other, said side walls being offset outwardly intermediate their upper and lower edges and said dividing wall being materially thicker from its bottom upwardly to a point intermediate the bottom 60 and roof of said furnace to thereby form relatively narrow flow paths for the molten glass and relatively wider flow paths for the products of combustion above the glass.
7. In a glass melting furnace comprising 65 a rectangular body portion composed of a bottom wall, side walls, front and back end walls and roof, a dividing wall extending longitudinally of said furnace from end to end and bottom to roof forming two chambers, openings through said dividing wall adjacent one end for the passage of glass 70 and the products of combustion from one chamber to the other, said side walls being offset outwardly intermediate their upper 75 and lower edges and said dividing wall being materially thicker from its bottom upwardly to a point intermediate the bottom and roof of said furnace to thereby form relatively narrow flow paths for the molten 80 glass and relatively wider flow paths for the products of combustion above the glass, and means for cooling the thicker portion of said dividing wall.

In testimony whereof, I have hereunto signed by name.

WILLIAM A. YUNG.
